UNITED STATES PATENT OFFICE.

HENRY MATHEY, OF RONDOUT, NEW YORK.

MANUFACTURE OF LIME OR CEMENT.

SPECIFICATION forming part of Letters Patent No. 369,353, dated September 6, 1887.

Application filed January 4, 1887. Serial No. 223,364. (No model.)

To all whom it may concern:

Be it known that I, HENRY MATHEY, a citizen of the United States, residing at Rondout, in the county of Ulster and State of New York, 5 have invented certain new and useful Improvements in Kilns for the Manufacture of Lime or Cement; and I do hereby declare the following to be a full, clear, and exact description of the invention, such as will enable 10 others skilled in the art to which it appertains to make and use the same.

My invention relates to kilns for the manufacture of lime or cement; and it consists in a receiving-chamber provided with air-inlets 15 and openings for vapor-burners, a drawing-chamber provided with air-ducts leading therefrom to the top of the kiln, an automatic feed for feeding the material from the receiving to the drawing chamber, conveyers for automatically discharging the material from the drawing-chamber, and other details of construction, 20 which will be hereinafter described, and pointed out in the claims.

The accompanying drawing illustrates my 25 invention, and the several parts of the device are indicated by letters of reference marked thereon.

Referring more particularly to the drawing, the kiln proper consists of a shell or wall, A, 30 of suitable dimensions. The interior is a receiving-chamber, A', tapering or diminishing at A', so that the crushed and burned material falling from the cylinder H will concentrate at the bottom of the chamber. This chamber 35 is closed at the bottom by a reciprocating slide, C, actuated by a suitable crank arm or lever, d. This permits the material to fall at intervals into the drawing-chamber B, (which is preferably arched,) where it comes into contact with the cold air, and from whence it is 40 automatically conveyed by the screw-conveyers E to the floor of the pulverizers or to the pulverizers direct.

It has been found by research and experiment that the hot cement suddenly coming 45 into contact with cold atmospheric air undergoes certain chemical reactions which give to it increased hydraulicity, as well as a desired shade of color. These reactions take place in 50 the chamber B. It is essential that the air be admitted while the cement is in its highest

state of heat, as the stone is then porous and better adapted to absorb the oxygen. It is also essential that the air be excluded from the chamber A', (except that admitted at the top 55 through the openings o for support of combustion,) as the admission of such air into the mass of the cement would reduce the temperature requisite in said chamber. To accomplish these results I have provided air-channels a, leading from chamber B, around chamber A', and thence through dust-chambers f to stack K.

It is understood that the cement-rock (or limestone) is first crushed and calcined under agitation, as described in my patents Nos. 65 330,603 and 339,309.

The operation is as follows: The crushed material from the revolving cylinder H is fed into chamber A', where it is met by the heat generated by means of the vapor-burners inserted in openings p. As the material gradually descends to the bottom of this chamber it passes through the last of the various changes and reactions relative to the expelling of the carbonic acid and water of crystallization. As 75 it reaches the bottom the reciprocating slide C, actuated by the rod d through the intervention of a cam, d', on shaft d', permits a certain portion at given intervals to pass into the chamber B. This chamber is open to the air, 80 and here the heated material comes into contact with the oxygen of the air, and as it falls toward the conveyers E there is an opportunity for the oxygen to reach all the particles. The ducts a create a strong draft, which 85 carries upward the hot air and deposits any fine material in the dust-chambers f. The material in chamber B is thus quickly reacted upon and cooled. It is obvious that the air-ducts a may be on the outside of the kiln instead of inside, as shown, without departing 90 from the spirit of my invention.

Having thus described my invention, what I claim as new, and desire to secure by Letters Patent, is—

1. A kiln provided with a material-receiving chamber, means for alternately and automatically opening and closing the same at or near the bottom, a drawing-chamber provided with means for withdrawing the material therefrom, and air-ducts leading therefrom, whereby a current of cold air is maintained in

said chamber and the material oxidized and cooled, as set forth.

2. In a kiln, the combination, with means for heating the material, of a receiving-chamber, means for automatically opening and closing its lower end, a drawing - chamber, and means for withdrawing the calcined material, and air-ducts leading from said chamber to

the top of the kiln, as and for the purpose set forth.

In testimony whereof I affix my signature in presence of two witnesses.

HENRY MATHEY.
